The present invention concerns a novel combination of active agents consisting of known fungicidal mercury compounds and known salts of 1,2-propylene-bis-dithiocarbamic acid and exhibiting a particularly favorable fungicidal activity.

The use of fungicidal organic mercury compounds in rice cultivation, particularly for the control of *Piricularia oryzae*, has already been disclosed. However, disadvantages are experienced during this process due to the high toxicity of the mercury compounds towards warm-blooded creatures and due to their phytotoxicity. It is necessary to keep the dosages as low as possible. Organic mercury compounds, for instance phenyl mercuric acetate, also have a phytotoxic activity towards certain varieties of rice and they cannot therefore be employed on all varieties of rice at the concentration required for effectiveness. It is also known that organic mercury compounds largely develop a curative (chemotherapeutic) activity. Their protective activity is relatively weak. In addition, the fungicidal organic mercury compounds are not effective against all diseases encountered in rice cultivation. Thus, they do not for instance develop a sufficient effect against *Corticium sasakii*.

It has also been disclosed that salts of 1,2-propylene-bis-dithiocarbamic acid can be employed as fungicides. However, until now nothing has been disclosed about the activities of these substances during the control of fungus diseases on rice.

It is an object of the present invention to provide novel synergistic combinations of active agents which have fungicidal properties and are particularly suitable for the control of diseases on rice. A further object consists in the indication of those fungicidal agents which only exhibit a low toxicity towards mammals. Other objects are evident from the following description and from the example.

It has been found that novel combinations of active agents from (1) fungicidal organic mercury compounds and (2) salts of 1,2-propylene-bis-dithiocarbamic acid exhibit a particularly good activity during the control of fungus diseases on rice.

The fact that no decrease in the curative activity takes place among the fungicidal mercury compounds while at the same time an increase in their protective activity is experienced when a part of the mercury compounds is replaced by salts of 1,2-propylene-bis-dithiocarbamic acid must be regarded as distinctly surprising.

The combinations of active agents according to the invention exhibit various advantages. Thus, their toxicity towards warm-blooded creatures and their phytotoxicity is only relatively slight. Moreover, the spectrum of the

2

diseases on rice which can at the same time be controlled by them is widened. The combinations of active agents exhibit a high protective activity and a curative effect at the same time.

5 The term "fungicidal organic mercury compounds" refers to the known mercury compounds which are employed for the control of fungus diseases. For the combination according to the invention, particular consideration may be given to organic mercury compounds of the general Formula I:

wherein

15 R represents aryl such as phenyl, alkylaryl such as methylphenyl, halogenoaryl such as chlorophenyl, a heterocyclic radical such as pyridine, or alkyl with 1 to 6 carbon atoms, and
X represents an inorganic acid radical such as halide, particularly iodide and chloride, or half an equivalent of sulphate, and organic acid radicals such as acetyl and sulphenic acid radicals.

20 The following may be mentioned in detail as examples of organic mercury compounds: phenyl mercuric acetate, phenyl mercuric iodide and phenyl mercuric chloride.

The term "salts of 1,2-propylene-bis-dithiocarbamic acid" quite generally refers to the salts of this bis-dithiocarbamic acid with a known fungicidal activity. The zinc,

30 manganese and nickel salts are particularly suitable. Mixed salts, for instance the manganese zinc mixed salt, also have a special activity. In this connection, the content of zinc 1,2-propylene-bis-dithiocarbamate may vary between 20 and 80%.

35 The proportions of the two groups of active agents in the mixture may be varied within wide limits. In general, the combination of the active agents may contain between 5 and 99 percent by weight, preferably between 80 and 95 percent by weight, of the bis-dithiocarbamate salt.

The combinations of active agents according to the invention exhibit a strong fungicidal activity on fungus diseases encountered in rice cultivation while their toxicity towards warm-blooded creatures is low. The effects develop rapidly and last for a long time. The combinations 45 of active agents are for instance active towards *Piricularia oryzae* and *Cochliobolus miyabeanus* and *Corticium sasakii*.

The combinations according to the invention may be applied by themselves or in the form of the usual compositions, such as emulsifiable concentrates, spray powders, pastes, soluble powders, dusting agents and granulates. These are prepared in known manner (cf., Agricultural Chemicals, March 1960, pages 35-38). The following may be mainly considered for use as assistants for this purpose:

55 solvents such as aromatic hydrocarbons (for instance xylene-, chlorinated aromatic hydrocarbons (for instance chlorobenzenes), paraffins (for instance petroleum fractions), alcohols (for instance methanol), amines (for instance ethanolamine) and water; carriers such as natural ground minerals (for instance kaolines, chalk) and synthetic ground minerals (for instance highly dispersed silicic acid); emulsifying agents such as non-ionic and anionic emulsifying agents (for instance polyethylene oxide esters of fatty acids, alkyl sulphonates); and dis-

persing agents such as lignin, spent sulphite liquors and methylcellulose.

The active agents according to the invention may be present in the compositions in the form of mixtures with other known active agents.

In general, the compositions contain between 0.1 and 95 percent by weight of the active agent, and preferably between 0.5 and 90 percent by weight.

The combinations of active agents according to the invention are applied by themselves or in the form of their compositions by the usual methods, for instance by spraying, sprinkling or dusting.

The following example is given for the purpose of illustrating the invention.

Example

Field test with *Piricularia oryzae* on water rice (*Oryza sativa japonica*), Type Norin 21.

The active agents are applied in the form of their aqueous suspensions. When mixtures of active agents are employed, aqueous suspensions of the individual active agents are first prepared separately. The suspensions are subsequently mixed. The preparation of the suspensions is carried out by the normal method with the use of an emulsifying agent.

Water rice is planted on plots of an area of 35 square meters. The plots are subjected to natural infection. The first treatment is carried out 14 days after planting, by sprinkling the plants with the suspension of the active agents. It is applied at the rate of 1,200 liters per hectare. A second treatment is carried out 14 days after the first treatment, by the same method. The evaluation is effected four weeks after the second treatment, 200 leaves from each plot being employed for an estimation of the degree of infestation. The degree of infestation expresses the infestation on the experimental plot as a percentage of the maximum possible infestation. From this result, it is possible to calculate the degree of activity, which specifies the percentage reduction of infestation compared with the untreated plot. The degree of activity may vary between 0 and 100, where 0 indicates that the infestation was just as high as for the untreated control and 100 indicates that an infestation has been prevented altogether.

The following table specifies the active agents, the contents of the active agents in the suspensions as well as the degree of infestation and the degree of activity. The stated data represent average readings from three repeated determinations.

It is evident from the following table that when the concentration of the active agent is 0.05% and also when the concentration of the active agent is 0.025%, zinc 1,2-propylene-bis-dithiocarbamate only has a low degree of activity. When phenyl mercuric acetate is applied at a 0.0043% concentration of the active agent, the achieved degree of activity is satisfactory for practical purposes. However, a considerable disadvantage of mercury compounds consists in the fact that they exhibit a high toxicity towards warm-blood creatures. An effort is therefore always made to keep the concentration of the active agent as low as possible in the case of mercury compounds. However, when compositions of the active agent with a content of 0.00215% of this active agent are employed, the degree of activity is already reduced to 44. This degree of activity is too low for practical purposes.

When use is made of a combination of active agents according to the invention, which for instance contains 0.025% of zinc 1,2-propylene-bis-dithiocarbamate and 0.00215% of phenyl mercuric acetate, the achieved degree of activity (77) is practically as high as the degree of activity (74) attained at a 0.0043% content of active agent with the mercury compound although only half the required amount of the mercury compound (degree of activity 44) has been applied in conjunction with a very small amount of zinc 1,2-propylene-bis-dithiocarbamate,

which on its own only exhibits a very low degree of activity (2). The degree of activity is a measure for the practical value of an active agent since it indicates both the protective and curative effects. The combinations of active agents according to the invention clearly exhibit a synergistic effect.

TABLE

	Active agents	Content of active agent, as percent	Degree of infestation on experimental plots	Degree of activity of the products
15	Zinc 1,2-propylene-bis-dithiocarbamate.	0.05	39.0	15
		0.025	44.9	2
	Nickel 1,2-propylene-bis-dithiocarbamate.	0.05	38.1	17
		0.025	46.2	0
	Zinc/manganese 1,2-propylene-bis-dithiocarbamate (1:1).	0.05	39.4	14
		0.025	44.9	2
	Phenyl mercuric acetate.	0.0043	10.6	77
		0.00215	25.7	44
20	Zinc 1,2-propylene-bis-dithiocarbamate+phenyl mercuric acetate.	0.025	11.9	74
		+0.00215		
	Nickel 1,2-propylene-bis-dithiocarbamate+phenyl mercuric acetate.	0.025	14.7	68
		+0.00215		
25	Zinc/manganese 1,2-propylene-bis-dithiocarbamate (1:1)+phenyl mercuric acetate.	0.025	13.3	71
		+0.00215		
	Untreated control.		45.8	0

30 We claim:

1. A method for controlling fungus diseases in rice which comprises contacting the plants with a fungicidal composition containing as active ingredients

(1) a compound of the formula

wherein R is a member selected from the group consisting of phenyl, methylphenyl, chlorophenyl and alkyl of 1-6 carbon atoms; and X is a member selected from the group consisting of an inorganic acid radical, acetyl and sulphenic acid radicals; and

(2) a member selected from the group consisting of zinc and nickel salts of 1,2-propylene-bis-dithiocarbamic acid and a zinc/manganese mixed salt of 1,2-propylene-bis-dithiocarbamic acid; the percent by weight of composition of (1) and (2) being about .002% and .025%.

2. A fungicidal composition containing as active fungicides

(1) a compound of the formula

wherein R is a member selected from the group consisting of phenyl, methylphenyl, chlorophenyl and alkyl of 1-6 carbon atoms; and X is a member selected from the group consisting of an inorganic acid radical, acetyl and sulphenic acid radicals; and

(2) a member selected from the group consisting of zinc and nickel salts of 1,2-propylene-bis-dithiocarbamic acid and a zinc/manganese mixed salt of 1,2-propylene-bis-dithiocarbamic acid; the percent by weight of composition of (1) and (2) being about .002% and .025%.

3. The method of claim 1 wherein

(1) is phenyl mercuric acetate and

(2) is the zinc salt of 1,2-propylene-bis-dithiocarbamate.

4. The method of claim 1 wherein

(1) is phenyl mercuric acetate and

(2) is the nickel salt of 1,2-propylene-bis-dithiocarbamate.

5. The method of claim 1 wherein

(1) is phenyl mercuric acetate and

- (2) is a zinc/manganese mixed salt of 1,2-propylene-bis-dithiocarbamate.
6. The composition of claim 2 wherein
- (1) is phenyl mercuric acetate and
  - (2) is zinc 1,2-propylene-bis-dithiocarbamate.
7. The composition of claim 2 wherein
- (1) is phenyl mercuric acetate and
  - (2) is nickel 1,2-propylene-bis-dithiocarbamate.
8. The composition of claim 2 wherein
- (1) is phenyl mercuric acetate and
  - (2) is a zinc/manganese mixed salt of 1,2-propylene-bis-dithiocarbamate.
